UNITED STATES PATENT OFFICE

SAMUEL S. MATTHES, OF MANSFIELD, OHIO, ASSIGNOR TO THE OHIO BRASS COMPANY,
OF MANSFIELD, OHIO, A CORPORATION OF NEW JERSEY

CONDUCTOR SUPPORT

Application filed December 1, 1928. Serial No. 323,110.

My invention relates to overhead trolley wire supports and particularly in connection with such supports as are adapted to permit the crossing of two or more trolley wires and 5 provided with means for insulating one or more of the wires from the other conductors.

One of the objects of my invention is to provide a device which is flexible in that insulated relation between any one or more of 10 a plurality of trolley wires may be varied at will.

My invention relates particularly to such devices as are known in the art as overhead trolley frogs and switches and overhead 15 crossings, either fixed or adjustable.

It is invariably the case where two or more trolley wires cross each other that at the junction of crossing a device known as an overhead crossing, either fixed or adjustable, 20 is employed and also where a branch or turnout trolley wire occurs from a main line, a switch or frog is employed. It also often happens that it is desirable to insulate one or more of the trolley wires from the 25 other wire or wires at or adjacent the point of crossing or turnout, and in the past, it has been the practice to insert in one or more of the trolley lines a device known as a section insulator and which is spaced from the crossing or switch and connected thereto by a short 30 length of trolley wire as shown in Patent 1,465,308 issued August 21st, 1923.

My invention is to improve upon such conditions and combine in one device, which is 35 so constructed that the device can very easily be changed to an ordinary switch or crossing which can be thrown into combination with insulating attachments which will insulate any one or more of the trolley wires and by 40 so doing, a more compact overhead arrangement can be constructed and which is neater in appearance and cheaper to construct.

There are, at the present time, devices made 45 in the form of crossings which are permanently arranged to insulate one wire from another, but such devices are very heavy compared with the invention I herein disclose and such devices are more or less special. With my arrangement it is only necessary to carry the live portion and the insulated portion in

stock, and such parts can then be combined to suit the requirements, or the live portion may be employed without the insulating portion.

There is also further advantage in my arrangement in that failure of one of the parts does not involve loss of the entire device and worn out parts can be renewed separately, quickly and with a least amount of disturbance to the other parts of the combination, and this is a very important item in attempting to make changes in a device once installed and where the cars are continually in operation.

My invention resides in the new and novel 65 construction, combination and relation of the various parts described in this specification and shown in the attached drawing.

In the drawing:—

Fig. 1 is a top view of a frog or switch having two insulated members and one live member.

Fig. 2 is a side view of Fig. 1 with a small part in section.

Fig. 3 is a section on the line 3—3 of Fig. 2. 75

Fig. 4 is an end attachment for maintaining such trolley wire in position as is not insulated from the main portion of the switch.

In one preferred embodiment of my invention I employ a body member 1 having a through wire groove 2 and a branch wire groove 3 on the upper face and a clamping member 4 held in place by means of the bolts 5 and is used to clamp such wire or wires as 85 are not insulated from the member 1, as, for instance, the trolley wire 6. The channel 2 in the arm 7 is the same as the channel 3 in the arm 8 and likewise the arm 9 has a channel 90 the same as the other arms.

The side walls of the arms 7, 8 and 9 are provided with hook members 10 which form a recess 11. In connection with the arm 7 I have shown a rotatable clamping member 12 which has integrally formed therewith transversely projecting lugs 13 and a cam shaped end portion 14, the surface of which is eccentric with the center of the lugs 13. The clamp is also provided with an inverted groove portion formed by spaced depending 100

lips 15 which are adapted to be folded below the trolley wire 6 and partially encircle the same after the clamp 12 has been placed in position.

Having placed the wire 6 in the groove, the clamping member 12 is then inserted in the groove in an upright position with the lugs 13 interlocked in the recesses 11. The clamp 12 is then braced downwardly to a horizontal position until the trolley wire 6 rests in a groove formed by the lips 15. During the rotating operation the clamping portion 14 gradually braces the trolley wire 6 downwardly into the bottom of the groove 2 and when the lips 15 are then folded about the wire, the trolley wire will then be held in a fixed relation with respect to the arm 7 and the clamp 4 will prevent the wire being drawn out.

Such a clamping member may be applied to each one of the arms 7, 8 and 9, thereby producing what is termed a live frog, or if they are applied to all of the projecting arms on a crossing, either fixed or adjustable, they will form therewith what is known as a live fixed or adjustable cross-over. I make no claim for such a device as it is clearly shown in my prior Patent No. 1,682,136 dated August 28th, 1928, but mention it as being one of the arrangements which is possible with my invention.

In the device shown in Figs. 1 and 2, I have shown two trolley wires 16 and 17 as insulated from each other and from the wire 6 and this is brought about by applying to the arms 8 and 9 a removable end member 18 which has a projecting portion 19 adapted to be positioned in the groove 3 or may be applied to the groove in any of the other two arms. The portion 19 has a transverse passage 20 to receive the through bolt or pin 21.

The end member being positioned in the groove 3, the pin 21 is then positioned within the recess 11 and the passage 20 and a cotter pin 22 inserted to prevent removal of the pin 21. This will lock the end member 18 in position excepting when the pin 21 is removed intentionally and will prevent the end member 20 being moved out of position in a longitudinal direction or in a vertical direction. As I do not desire the end member 18 to rotate about the pin 21, I extend the end 23 of the portion 19 so that it will form a brace by engaging with the bottom surface of the groove 3. The member 18 is provided at its lower edge with a shoulder 24 which butts against the end face of the arm 8 and forms therefore a smooth run for a current collector from the arm 8 to the end member 18 or vice versa.

The lower face of the body member 1 is provided with ribs 25 which are extensions inwardly of the arms 7, 8 and 9, and act as guides on the lower surface of the frogs for the moving current collector.

Secured to the end member 18 is an insulating member 26 and bolts or rivets 27 hold the parts in place. The insulating member 26 may be made as long as the requirements demand.

To the opposite end of the member 26 is secured another end member 28 and secured in place by means of bolts or rivets 29. The end member 28 has a projection 30 provided with a passage 31 to receive the trolley wire 16 and having set screws 32 to engage the wire to grip and hold it in position.

The arm 9 is also provided with an insulating device as just described. If desired, the arm 7 may also be provided with insulating attachment or any one of the arms only may have the insulated attachment.

It will be recognized by those skilled in the art that I have produced a very flexible device which can be made to meet a number of varying conditions and with a minimum number of parts to be maintained in stock by the user and that it will be very easy after the device has been installed to change the conditions as desired, or to remove the parts with a minimum amount of labor, time and expense.

It will also be recognized that those skilled in the art, such as manufacturers and users of related classes of devices, that the same arrangement may be carried out in connection with live, fixed and adjustable crossovers as already stated.

The end portion 19 can be made if desired without the brace 13 such that the insulating portion can be positioned very much the same as the clamping member 12. This, however, would permit a relative movement between the body member 1 and the end member 18 about the pin 21 as an axis, which may be to advantage over some conditions.

Having described my invention I claim:

A trolley wire support arranged to receive a plurality of trolley wires comprising a body member, a rotary clamp mounted on the body and rotatable into position relative to the body to clamp one of the trolley wires therebetween and having means rotatable therewith to be attached directly to the trolley wire to lock said clamp against backward rotation, a non-rotatable end member mounted on the body and removably secured thereto, an insulating member secured to the end member and having a guiding edge for a movable current collector, a second end member secured to the insulating member in spaced and insulated relation to the first end member and having means to receive and hold one of the trolley wires, the first said end member being removable from the body without disturbing the wires secured to the second end member or to the rotary clamp.

In testimony whereof I affix my signature.

SAMUEL S. MATTHES.
